CYLINDER, PISTON, AND CRANKSHAFT
ARRANGEMENTWilson Mayne Allisen, Knockshegowna, Swin-
burne, O. F. S., Union of South AfricaApplication December 28, 1940, Serial No. 372,134
In the Union of South Africa January 2, 1940

2 Claims. (Cl. 123—43)

This invention relates to a new and improved cylinder and piston arrangement and its relation to the crank pin member assembly adapted for the development of power for any purpose as, for example, prime movers or pumps.

An object of the invention is to provide means for operating pistons and the cylinders cooperating with them relative to a rotational mass, such as a flywheel or crank pin carrying member, in such a manner that the pistons and cylinders have differing rotational or fundamentally rotational paths which cause alternating increasing and decreasing volumetric capacities between the cylinder heads and piston crowns.

It is the purpose of this invention to provide means whereby such differing volumetric capacities are useful in any manner of pumping or prime mover operations which require variable volume sequence.

It is therefore an object of this invention to provide a mechanism in which the loading due to reciprocating masses is reduced to a minimum.

A further object is to provide a mechanism in which the rotation of the cylinder assembly combined with the rotation of the crank pin assembly in different planes gives a smooth and continuous motion with the least amount of resistance due to the forces of inertia.

A further object is to provide a mechanism of the type described in which the crank pins being evenly spaced eliminate torsional strain or vibration and which permit the use of ball or roller-type bearings on said crank pins.

It is a further object to produce a mechanism in which the angle of thrust from the piston remains in the range of usable pressures longer, and in which the conversion of gas pressure to torque is an improvement over the present crank mechanism.

A further object is to provide a mechanism having inherent fundamentals of design which may be calculated for the most advantageous angles of thrust to give a longer stroke-to-bore ratio, and in which when applied to compression ignition work, where pressure is very high for a given volumetric capacity per cylinder, the piston area, due to the longer stroke-to-bore ratio, may be less than in prior devices, thus reducing the pressure on connecting rod bearings and bearings throughout the mechanism.

A further object is to provide a mechanism in which, when operated as a two-cycle engine with ported cylinders, the centrifugal force due to the rotation of the assemblies will assist in exhaust scavenging, and which in two-cycle operation

may use rotation of the cylinder assembly around the central spindle as a rotary valve for the admission of the air charge.

Other objects and advantages lie in the ability to use a single cam for fuel pump operation providing accurate means of controlling the required amount of fuel to individual cylinders with the elimination of piping under injection pressures. Moreover, the centrifugal force developed by the cylinder assembly can be used in a liquid cooled engine to maintain circulation.

A further object is to provide a mechanism which, in addition to the improvement of the angle of thrust, provides means in the fuel injection engine whereby, due to the fall-back of the connecting rods while the piston approaches top dead center, the speed of the piston is reduced and the injection of fuel may be undertaken through a smaller angle of rotation, thus avoiding the danger of undesirable pressures.

In addition to the foregoing objects, it is one of the purposes of this invention to provide a mechanism in which the layout gives the maximum of volumetric capacity with the minimum of frontal area, and at the same time greater accessibility to the moving parts.

Other objects and advantages will appear as the description proceeds, and it will become apparent that whether my invention is adapted to a pump or to a prime mover the same basic principle is involved. It will be noted that two primary axes for rotation are involved. This may take the form of a single spindle bent upon itself or separate members componently constructed. A predetermined of the angle between the carrier spindle and the cylinder or central spindle must be governed by certain considerations of the bore-to-stroke ratio of the pistons, but, generally speaking, the greatest efficiency will be secured when the two spindles form an obtuse angle as near as possible to a right angle. It will be appreciated that, due to the size of the connecting rods and the necessity for pins to carry the connecting rods and other mechanical factors, it is not feasible to mount the cylinder assembly and crank pin carrier at absolute right angles.

In the simpler form of my invention the cylinder assembly is of the barrel rotary type in which each cylinder bore is parallel to the bore into which the cylinder assembly spindle is fitted. However, this is not an essential feature, and it will be noted that in certain embodiments of my invention, for reasons which will be discussed later, the cylinders are mounted in the bore at a

predetermined angle to the bore of the cylinder assembly. Means are provided to synchronize the rotation of the cylinder assembly with the rotation of the crank pin carrier. These means may be used to transmit power to and operate the accessories necessary to the functioning of the unit in accordance with the purposes for which it is used. The basic principle involved may be applied to many types of prime movers whether operated by ignition combustion, compression combustion, or compressed air, and while in this application I illustrate and disclose specific embodiments it will be understood that these embodiments are merely for the purpose of illustration of the application of the principle. It will also be understood that duplication and multiplication of cylinders and pistons may be made and balanced assemblies mounted on either side on a common crank pin carrier, thus balancing side thrusts on the crank pin carrier bearings, and that various combinations of the valve operation, lubrication and cooling may be adopted. It will be also understood that when used as a prime mover, power may be taken from either end, that is, from a shaft connected by suitable gearing, or other means to the crank pin carrier or from the cylinder-carrying tube.

In the accompanying drawings which illustrate certain embodiments of my invention—

Fig. 1 is a side elevation of an assembly employing cylinders, pistons, crank pin carrier and connecting rods, and synchronization of crank pin carrier and cylinder assembly;

Fig. 2 illustrates a modified type of connecting rod;

Fig. 3 is a view of two units embodying my invention connected to a common drive shaft;

Fig. 4 is a cross-sectional view, taken on the line 4—4 of Fig. 6, showing the application of my principle to a compression ignition four-cycle engine;

Fig. 5 is a detailed view of the reduction gearing used to operate the motor accessories;

Fig. 6 is a cross-sectional view of a four-cycle motor, taken on the line 6—6 of Fig. 4;

Fig. 7 is a cross-sectional view, taken on the line 7—7 of Fig. 4;

Fig. 8 is a cross-sectional view, taken on the line 8—8 of Fig. 4.

In Figs. 4 and 6 the rear cylinders have been omitted from the drawings for the purposes of clarity and in order to avoid confusion.

Referring to Fig. 1, I provide a spindle 10 which is formed in an obtuse angle 11 having an upper portion 12 and a lower portion 13. Mounted on the upper portion 12 is a cylinder-bearing sleeve 14 including the cylinders 15 and 16. Mounted on the lower portion 13 is a crank pin carrier member 17 which may engage with or merge into a drive shaft 18.

For the purposes of synchronizing the crank pin carrier and the cylinder assembly 20, a ring gear 21 is mounted on the lower portion of the cylinder assembly 20 and engages a similar gear 22 on the crank pin carrier. It will be understood that both the cylinder assembly and the crank pin carrier rotate around their respective axes, the cylinder assembly around the spindle portion 12 and the crank pin carrier around the spindle portion 13.

Working in the cylinders 15 and 16 are pistons 23 and 24. The piston 23 is provided with a connecting rod 25 which is pivotally connected with the crank pin 26. A similar connecting rod 27 connects with the crank pin 28. The crank pins

26 and 28 are mounted in the carrier 17 for rotation therein and are provided with suitable bearings 29. The crank pin carrier 17 may be made of sufficient weight to act as a flywheel. As the unit rotates, the crank pin carrier 17 revolves in one plane, the cylinder assembly 20 rotates in another plane, while the pistons operate in a basically diagonal plane, with the result that the position of the pistons with relation to the cylinder varies from the top to the bottom upon this rotation. It will be appreciated that where the unit is used as a pump, suitable valves may be installed, and where used as a prime mover, apparatus such as will be hereinafter described, will also be provided.

In some instances where the angles of movement on the connecting rod are relatively small, a bearingless connection may be made between the piston and the crank pin, as shown in Fig. 2, where the piston 30 is fixedly connected to the flexible connecting rod 31 and to the crank pin 32. The connecting rod 31 is relatively thin in cross section and will have sufficient flexibility and spring to prevent jamming. It will be seen in this construction, as shown in Fig. 1, that the pistons operate in the cylinder with a minimum of side thrusts and that a long stroke-to-bore ratio is possible due to the relative positions and motion of the crank pin carrier and the cylinder assembly. A variation of the angle 11 will create a difference in the bore-to-stroke ratio, as will also a variation of the pitch circle centers of the spindle 10 and the cylinders 15 and 16. A further variation of bore-to-stroke ratio may be brought about by giving the cylinders angularity, that is, by mounting them at an angle to the bore of the spindle. It will also be seen that the construction provides possibilities of design in the casing 33 whereby with the removal of the door 34 the various moving parts are readily accessible for repair or adjustment.

In the modification, shown in Figs. 4, 5, 6, 7 and 8, the principles apply to a compression combustion four-cylinder four-cycle motor. In this construction the spindles 40 and 41 may be of a single piece or joined together by the elbow 42 or may be built up or formed of a number of pieces. The cylinder assembly 43 is mounted upon the spindle 41 which is hollow, for the purposes hereinafter described. Four cylinders, A, B, C and D, are provided. The cylinders are each provided with a piston 45 and a connecting rod 46 which is pivotally mounted at 47 to a pin 48, in turn pivotally mounted in the sockets 49, so that the relationship of the connecting rod with the piston is such that movement in any direction is possible. It will be noted that the cylinders A, B, C and D are mounted at a slight angle to the spindle 41 which allows the connecting rod a slight fall-back in operation, which causes the piston to approach the top of the cylinder at a slightly decreased speed.

For the purpose of synchronizing the cylinder assembly and the crank pin carrier on the assembly, I provide a hub 50 at the bottom of the cylinder assembly 43 which carries a beveled gear 51. The beveled gear 51 engages a ring gear 52 mounted on the sleeve 53 and is affixed thereto by the key 54. Also mounted on the sleeve 53 is a planetary gear mount 55 affixed to the sleeve by the key 56 and carrying the planetary gears 57. Mounted on the sleeve 58 and affixed to the spindle 40 by the key 59 is an annulus 60 which engages the outer teeth of the planetary gears 57. The inner teeth of the planetary gears 57

engage the teeth 61 on the ring sun pinion 62 which is affixed to the inner portion 63 of the crank pin carrier 64. A plate sleeve 65 is bolted to the inner section of the crank pin carrier 64 and extends along the spindle 40 where it may be bolted to the drive shaft 66 and held by the sleeve 67. The crank pin carrier 64 carries crank pins 70 mounted for rotation in suitable bearings 71 and having a pivot 72 at their outer ends to engage the connecting rod 46 at 73.

A section of the spindle 41 is provided with teeth 80 which engage the gears 81. The gears 81 are mounted on the same shaft with the gears 82 in the cylinder assembly and are keyed thereto. The gears 82 engage teeth 83 on the sleeve 84 mounted on the spindle 41 to rotate said sleeve at a ratio of one-to-two to the rotation of the cylinder assembly. Mounted on the sleeve 84 is a ring 85 having high points 86 adapted to operate the air intake valves of the cylinders. Air intake valves 87 are provided for each cylinder. These valves are mounted on the section 88 of the cylinder assembly and are provided with springs 89 which keep them normally closed. The valve rod 90 has a tappet 91 which is engaged by the high point 86 of the cam to open the valve on the air intake stroke of the cylinder.

Fuel injectors 95 are mounted in the cylinder heads and are operated by a cam 96 mounted on the ring 111 on the internally threaded sleeve 112. The sleeve 84 and the internally threaded sleeve 112 are provided with sharply pitched threads 113. The sleeve 112 performs the function of a fuel control and may be operated by the mechanism 114 so that the endwise movement of the sleeve 112 will determine the extent to which the cam 96 will operate the fuel injectors 95. Because of the sharply pitched threads 113 the endwise movement of the sleeve 112 will cause a relative turning of the sleeve 112 and therefore of the cam 96, thus keeping the injection period synchronized. It will be noted that the mechanism 114 has a rod 115 extending into the hollow spindle engaging the rod 116 which controls the sleeve 112. This mechanism is of course optional and any suitable means may be used to control the throttle member.

Fuel is fed to the injectors by means of the tube 97 running to the annulus 98 fed by the pipe 100 through the hollow spindle 41. Exhaust valves 101 are also mounted in the cylinder heads and lead to the manifolds 102. The valves 101 are normally kept closed by the springs 103 and have stems 104 pivoted to the rocker arms 105 mounted at 106 to the extension 107. The other end of the rocker arms 105 engage rods 108 which are adapted to be engaged by the high points of the cams 109 for the cylinders A and B, and 110 for the cylinders C and D. As shown in Figure 4, the cylinder A is about to start the power stroke and the cam 96 is engaging the fuel injector for that cylinder. As shown in Fig. 6, the piston of cylinder B is half way through the intake stroke and the air valve is open. The piston of cylinder C is starting the exhaust stroke while the piston in cylinder D is half way through the exhaust stroke.

It will be understood that the arrangement of cylinders shown in this application is only for the purpose of clearly disclosing the invention in its most simplified form and that in actual practice an odd number of cylinders would be used in order to get evenly spaced firing periods where the four-cycle principle is used.

A circulation system may be provided in which

a cooling medium is introduced through the pipe 120 and the channel 121 into the water jacket 122. The centrifugal force caused by the rotation of the cylinder assembly will aid the circulation through the jacket. A return channel 123 in a pipe 124 is provided to complete the circulation. While I have shown a liquid cooling system, this is purely optional and the cylinders may be air-cooled or may be cooled by a combination of liquid and air.

Suitable bearings 125 and 126 are interposed between the cylinder assembly and the shaft. Other bearings of the ball and roller type may be interposed and used in other moving parts.

The motor casing 130 is made in sections for ready accessibility to all of the moving parts and is provided with air ports 131. By the removal of the lower casing it is possible to get at the pistons and crank pins as well as the crank pin carrier. By removing the upper section of the casing the valves and cylinder heads are readily accessible.

It will be appreciated that my invention discloses an engine fundamentally of the rotary type which is adaptable to either two-cycle or four-cycle operation when equipped with conventional ports or valves. As shown in Fig. 8, a cylinder cover 135 may be provided to prevent the cylinder assembly from wasting power by air churning. Due to the fact that the cylinders are set at a slight angle in the central spindle, the connecting rods have a certain fall-back which results in the piston approaching the cylinder head at a slightly reduced speed which permits the injection of fuel in the cylinder head at a relatively reduced angle of rotation of the crank pin carrier.

It will also be appreciated that the engine may be readily adapted to a carbureted electric ignition engine for ignition combustion.

Because of relatively large individual cylinder capacity, fuel metering is easy, and undesirable pressures due to any error in metering are reduced. The use of the single cam avoids timing errors. For these reasons a smoother running motor is possible. It will also be apparent that the design makes possible the use of very short connecting rods relative to stroke ratio without detrimental side thrusts due to angularity. Centrifugal force will assist the scavenging both on the exhaust outwardly and the transfer inwardly. The rotation of the cylinder assembly synchronized with the crank pin carrier gives a flywheel effect to the entire motor which is particularly desirable in compression combustion engines.

It will also be apparent that because of the design it is possible to space the crank pins evenly with relation to each other and in the same plane, which results in smoother operation. This also makes possible the use of the flexible connecting rod, shown in Fig. 2, which will be desirable with certain types of motors.

Because of the flexibility inherent in the design, there are a number of factors which simplify the building of the motor to a definite stroke-to-bore ratio. The changing of the angle between the cylinder assembly carrying spindle and the crank pin carrier spindle, the changing of the radii of the crank pins, the changing of the length of the connecting rods, and the angle at which the cylinders are positioned in the cylinder assembly with respect to the cylinder assembly spindle, all vary the stroke-to-bore ratio, and in building of the motor, the angles,

radii and length of the connecting rods are predetermined to accomplish the desired result.

As shown in Fig. 3, a pair of motors 140 and 141 may be joined by a common shaft 142 to a drive shaft 143 by means of the gears 144 and 145. The position of the shaft 143 with respect to the motors 140 and 141 may be varied to suit the purpose to which the unit is to be put by the use of suitable gearing and the angle thereof can readily be changed.

I claim:

1. In a motor having cylinders adapted to rotate about a central spindle, and fuel injectors mounted in said cylinders, said fuel injectors having operating tappets mounted therein, fuel injector actuating means comprising a sleeve mounted on said spindle, gear means interengaging said sleeve and spindle whereby said sleeve is rotated at a predetermined rate, sharply pitched threads on said sleeves, an internally threaded sleeve engaging said sharply pitched threads, a cam ring on said second-mentioned

sleeve adapted to engage and operate said fuel injector tappets, said cam ring having a beveled face, and means for rotating said second-mentioned sleeve with relation to said first-mentioned sleeve whereby the extent of engagement of said cam with said tappets can be controlled.

2. Fuel injector actuating means for fuel injectors having operating tappets, said actuating means comprising a rotatable sleeve, gear means 10 engaging said sleeve and rotating said sleeve at a predetermined rate, sharply pitched threads on said sleeve, an internally threaded sleeve engaging said sharply pitched threads, a cam ring on said second-mentioned sleeve adapted to engage and operate said fuel injector tappets, said cam ring having a beveled face, and means for rotating said second-mentioned sleeve with relation to said first-mentioned sleeve whereby the extent of engagement of said cam with said tappets may be controlled.

W. M. ALLISON.
